FIG. 5.

UNITED STATES PATENT OFFICE.

LEOPOLD ADELHOFER, OF NEW YORK, N. Y.

AUTOMATIC FEEDING ATTACHMENT FOR PRINTING-PRESSES.

1,300,803.

Specification of Letters Patent. Patented Apr. 15, 1919.

Application filed January 17, 1919. Serial No. 271,678.

To all whom it may concern:

Be it known that I, LEOPOLD ADELHOFER, a subject of the King of Hungary, and a resident of the city of New York, in the county of New York and State of New York, have invented certain new and useful Improvements in Automatic Feeding Attachments for Printing-Presses, of which the following is a specification.

10 The present invention relates to printing presses of the bed- and-platen type, and more particularly to an automatic feeding attachment therefor, which adapts the machine for printing on continuous strips of 15 indefinite length.

The main object of the invention is to provide a feeding attachment of the character mentioned, which is simple in construction, efficient in operation and which can be 20 mounted upon a printing press of the bed- and-platen type without necessitating material changes in the construction of the latter.

With these and other objects in view, which will more fully appear as the nature 25 of the invention is better understood, the same consists in the combination, arrangement, and construction of parts hereinafter described, pointed out in the appended claims and illustrated in the accompanying 30 drawings, it being understood that many changes may be made in the size and proportion of the several parts and details of construction within the scope of the appended claims without departing from the spirit 35 or sacrificing any of the advantages of the invention.

One of the many possible embodiments of the invention is illustrated in the accompanying drawings, in which:—

40 Figure 1 is a side elevation of a platen printing press with the feeding attachment mounted thereon; Fig. 2 is a top plan view thereof, on a larger scale; Fig. 3 is a vertical section taken through the feeding attachment; Fig. 4 is a top plan view of said attachment; and Fig. 5 is a section taken on line 5—5 of Fig. 4, on a larger scale.

45 In the drawings, only as much has been shown of the printing press as is necessary 50 to understand the invention, and while herein a printing press of specific form is dis-

closed, the attachment may be mounted on other presses just as well, as will hereinafter appear.

Referring now to the drawings, the numeral 10 indicates the frame of the press, in which the operative parts are supported, including a platen 11 and a swinging bed 12, which carries the form. This bed is supported by arms 13 which are oscillatably 55 mounted upon a shaft 14. A continuously rotating gear 15, receiving motion from the driving shaft of the press (not shown), is mounted upon the press frame. The platen is on machines of this type mounted so 60 as to have a rocking motion. When applying the feeding attachment, forming the subject matter of the present application for Letters Patent, upon the press, first the platen is locked permanently in the position 65 which it occupies when receiving the impression. The means for locking the platen is not shown, as it does not form part of the invention.

70 The feeding attachment comprises a substantially horizontally disposed table 16, that is bolted to the bed 12 and carries bearings 17, in which is rotatably mounted a lower feeding roller 18, which co-operates with an upper feeding roller 19. These rollers extend transversely of the press, the upper roller being under the tension of springs 20, for the well-known purpose. On the table 16 are furthermore mounted, in rear of the feeding rollers, bearings 21 in which 75 is rotatably mounted a shaft 22, extending parallel to the said feeding rollers and carrying wind-up reels 23. A plurality of these wind-up reels may be mounted upon the said shaft, if a plurality of narrow webs or paper strips are to be simultaneously printed upon, for instance when printing labels, or a single wind-up reel, if one wider web is to be 80 printed upon. The webs or continuous paper strips 24 are led from supply reels 85 (not shown) up between the platen and bed of the press over a guide roller 25, in front of the feeding rollers, and thence between the said feeding rollers to the wind-up reels. The feeding rollers and the wind-up reels 90 are driven from the gear 15 in the following manner:—To the bed 11 is fixedly attached 95

a downwardly extending frame 26, to which is pivoted at 27 a lever 28. The distance between this lever and the frame 26 may be adjusted, for instance, by a set-screw 29. 5 The lever 28 is provided with a longitudinal slot 30, through which extends a spindle 31, carrying a gear 32, that meshes with a gear 33, the latter being rotatably mounted upon the pivot 27 above mentioned and is in mesh 10 with a pinion 34. This pinion is fixedly attached to the lower feeding roller 18. The gear 32 is adapted to mesh with the gear 15, when the bed 12 is in its outermost position, that is to say in non-printing position. 15 The shaft 22, upon which the wind-up reels 23 are mounted, is driven from the lower feeding roller 18. To this roller is attached for this purpose a sprocket wheel 35, over which runs a chain 36, in mesh with 20 a sprocket wheel 37, the latter being loosely mounted upon the shaft 22. On this shaft is loosely mounted a bushing 38, that constitutes one of the journals thereof. Between the sprocket 37 and this bushing is 25 inserted a washer 39, a spring 40 on the shaft 22 serving to force the gear 37 against the said washer. Against the other side of the bushing abuts a washer 41, in contact with a gear 42, that is loosely mounted upon 30 the shaft 22. This gear meshes with a pinion 43, that is attached to the spindle 44 of a spring motor. This motor includes a spring housing 45, containing a spring 46, the inner end of which is secured to the spindle 44, 35 while its other end is fastened to the said spring housing. With the spring housing is made integral, or there may be attached thereto, a gear 47, that meshes with a pinion 48. The last-named pinion is fixed to 40 the shaft 22, and provided with a plurality of pins 49, that are adapted to engage a spring stop 50. This spring stop is secured to the frame 10 of the press, and is in engagement with a pin 49 when the bed 12 is 45 in its outermost position, shown in Fig. 1 of the drawings.

The operation of the feeding attachment is as follows:—When the elements of the printing press and feeding attachment are in the 50 positions shown in Fig. 1 of the drawings, that is to say when the bed 12 is in its outermost position, the gear 32 meshes with the continuously rotating gear 15 of the printing press. Rotation is thus imparted, by the 55 intermediary of the gear 33 and pinion 34, to the feeding rollers, thereby advancing the webs 24 a distance that is determined by the time during which the train of gears actuating the said feeding rollers is in motion. At the same time, the sprocket wheel 37 is rotated, its rotation being transmitted to the gear 42, and by the latter to the pinion 43. Inasmuch as in the position shown in Fig. 1 of the drawings one of the pins 49 60 of the pinion 48 is engaged by the stop 50,

the shaft 22, upon which the wind-up reels 23 are mounted, does not rotate. While the elements are in the positions shown in Fig. 1 of the drawings, the wind-up reels are thus not rotated, the rotation of the sprocket 70 wheel 37 resulting only in winding up the spring 46 in the housing 45. When, therefore, after the bed 12 moves toward the platen 11, the pin 49, previously in engagement with the stop 50, is disengaged from 75 the said stop. The gear 47, under the action of the spring 46, causes a movement of the shaft 22, winding up the webs on the said reels as far as the feeding rollers will permit. In other words, the reels take up the 80 slack of the webs between the feeding rollers and the wind-up reels.

After the impression has been made by the form on the webs, the bed moves outward, bringing the gear 32 in mesh with the gear 85 15, with the result that the cycle of operation described is repeated.

The extent of the feed may be varied by replacing the gear 32 with a larger one or a smaller one, according to the requirements. 90 To permit a gear of larger or smaller size to be interposed between the gears 33 and 15, the distance between the lever 28 and the frame 26 must be varied by the set-screw 29, the slot 30 in the lever 28 being provided to 95 accommodate gears of varying sizes.

What I claim is:—

1. A paper feeding attachment for printing presses of the type including a stationary platen, a reciprocating bed holding the form 100 and a continuously rotating gear, the combination with said bed, of feeding rollers mounted thereon, and a train of gears for actuating said feeding rollers, one member of said train being brought into mesh with said continuously rotating gear when said bed approaches the end of the stroke away from said platen and unmeshed when said bed moves in the opposite direction.

2. The combination claimed in claim 1 110 having means for varying the speed of the feeding rollers.

3. A paper feeding attachment for printing presses of the type including a stationary platen, a reciprocating bed holding the form 115 and a continuously rotating gear, the combination with said bed, of feeding rollers mounted thereon, a train of gears for actuating said feeding rollers, one member of said train being brought into mesh with said continuously rotating gear when said bed approaches the end of the stroke away from said platen and unmeshed when said bed moves in the opposite direction, a wind-up reel upon said bed, and a gearing between 120 one of said feeding rollers and said wind-up reel.

4. The combination claimed in claim 3, said gearing including a spring motor wound up during the motion of the feeding rollers 130

and actuating said wind-up reels when said bed moves toward printing position.

5. A paper feeding attachment for printing presses of the type including a stationary platen, a reciprocating bed holding the form and a continuously rotating gear, the combination with said bed, of feeding rollers mounted thereon, and a train of gears for actuating said feeding rollers, one member

of said train being brought into mesh with 10 said continuously rotating gear at times when said bed is out of contact with said platen.

Signed at New York, in the county of New York, and State of New York, this 15th 15 day of Jan. A. D. 1919.

LEOPOLD ADELHOFER.
